UNITED STATES PATENT OFFICE.

KENNETH F. LEES, OF NEW HAVEN, CONNECTICUT.

COMBINED LAMP AND ASH TRAY.

Application filed January 27, 1923. Serial No. 615,234.

To all whom it may concern:

Be it known that I, KENNETH F. LEES, a citizen of the United States, residing at New Haven, in the county of New Haven and 5 State of Connecticut, have invented a new and useful Improvement in Combined Lamps and Ash Trays; and I do hereby declare the following, when taken in connection with the accompanying drawings and 10 the characters of reference marked thereon, to be a full, clear, and exact description of the same, and which said drawings constitute part of this application, and represent, in—

15 Fig. 1 a rear view of a combined lamp and ash tray constructed in accordance with my invention.

Fig. 2 a side view of the same.

20 Fig. 3 a broken, sectional view on the line 3—3 of Fig. 2.

Fig. 4 a broken, sectional view on the line 4—4 of Fig. 3.

25 This invention relates to an improved lamp and ash tray, the object being to provide a lamp and ash tray which may be clamped to the arm of a chair, post of a bed, or other support, or used as an ordinary table lamp, and the invention consists in the construction as hereinafter described and 30 particularly recited in the claims.

In carrying out my invention, I employ a yoke 10, one end forming a bottom 11 and the other a stationary clip-arm 12. Pivotally connected with the yoke is a combined 35 ash tray and match holder 13, constructed in accordance with the invention set forth in my application, filed May 15, 1922, Serial No. 560,946. Connected with the bottom is a tubular post 14 formed on opposite sides 40 with vertical slots 15 and 16, the upper ends of which extend through segmental slots 17 and 18 formed in the clip-arm 12. By passing through the slots, the divided upper end of the post is reinforced and held 45 against inward or outward movement. Within the post is a spring 19, the upper end of which bears upon a lower clip-member 20, which is secured to the upper end of a tubular slide 21 surrounding the post, and 50 formed on opposite sides with finger-pieces 22 and also formed with segmental slots 31 and 32, through which the said post extends. The lower clip-member may be conveniently depressed by the said finger-pieces 22. Connected with the upper end of the post is a 55 lamp-stem 23, to which an ordinary lamp-

socket 24 may be attached to receive the usual bulb 25, on which is supported a lamp-shade 26 of usual construction. Preferably, the lamp-support 23 and post 14 will be connected by a coupling-collar 27, in one side of which is located a bushing 28, through which the usual electric-light-wire cord 29 passes, and this bushing also engages with the upper end of the post and, therefore, 60 forms a lock between the post and lamp-standard, to prevent one turning with respect to the other. The device may stand upon a table, in which case the ash tray forms a supporting base, or the clip-members 65 12 and 20 may engage with a chair arm 30, table, or other suitable support, so as to afford a convenient light for reading or working, and, at the same time, form a support for a combined ash tray and match 70 holder which can be turned on the yoke so as to stand in a horizontal position, irrespective of the position of the lamp. It is equally obvious that the lamp might be clamped to a vertical upright, in which case 75 80 the ash tray will be turned at a right angle, so as to maintain its horizontal position.

I thus provide, in a very convenient and attractive way, a combined lamp and ash tray adapted to be used as a table lamp, or 85 clamped to a suitable support.

I claim:

1. A combined lamp and ash tray comprising a yoke, an ash tray pivotally connected with said yoke, and a lamp-standard 90 mounted in said yoke.

2. A combined lamp and ash tray comprising a yoke, an ash tray pivotally connected with said yoke, a lamp-standard mounted in said yoke, and means for clamping 95 said standard to a support.

3. A combined lamp and ash tray comprising a yoke, an ash tray pivotally connected with said yoke, a lamp-standard mounted in said yoke, and two clip-members 100 and a spring in said standard tending to force one member toward the other.

4. A combined lamp and ash tray comprising a yoke with which the tray is pivotally connected, a post between the ends of 105 said yoke, a tubular slide on said post, a spring within said post, and tending to move the said slide upward, and a lamp-standard connected with the upper end of said post.

5. A combined lamp and ash tray comprising a yoke, one end of which forms a 110 base and the other a clip-arm, an ash tray

pivottally connected with said yoke, and adapted to stand in the plane of said base, a tubular post arranged between the ends of the yoke, said post formed with slots on 5 opposite sides, said clip-arm formed with segmental slots through which the upper ends of the post extend, a spring within said post, a clip-arm formed with segmental slots through which the post extends, a spring between the base and slide, a lamp-standard 10 connected with the upper end of said post,

a bushing interlocking said standard with said post, and providing passage for electric wires into the standard.

In testimony whereof, I have signed this 15 specification in the presence of two subscribing witnesses.

KENNETH F. LEES.
